COVERED BOWL

Herbert S. Barnhart, Scarsdale, N. Y., assignor to National Dairy Products Corporation, New York, N. Y., a corporation of Delaware

Application November 16, 1954, Serial No. 33,112

Term of patent 14 years

(Cl. D44—15)

FIG. 1.

The parts shown in full lines in Figure 1 are continued about the periphery.

I claim:

The ornamental design for a covered bowl, as shown and described.
